CLAIM

The ornamental design for a metal ribbon bracket assy for tap handle, as shown and described.

DESCRIPTION

FIG. 1 is a rear perspective view of the metal ribbon bracket assy for tap handle showing my new design;

FIG. 2 is a rear view thereof that shows how the bracket is attached to the metal ribbon;

FIG. 3 is a front view thereof;

FIG. 4 is a right side view thereof;

FIG. 5 is a left side view thereof;

FIG. 6 is a top view thereof; and,

FIG. 7 is a bottom view thereof.
